UNITED STATES PATENT OFFICE

171,015

SHEET OF DECORATIVE MATERIAL
OR THE LIKE

Clifford Brooks Stevens, Milwaukee, Wis., assignor to The Formica Company, a corporation of Ohio

Application December 31, 1952, Serial No. 22,951

Term of patent 3½ years

(Cl. D92—1)

To all whom it may concern:

Be it known that I, Clifford Brooks Stevens, a citizen of the United States, residing at Milwaukee, county of Milwaukee, and State of Wisconsin, have invented a new, original, and ornamental Design for a Sheet of Decorative Material or the like, of which the following is a specification, reference being had to the accompanying drawing forming a part thereof, in which

The figure is a plan view of the sheet of decorative material showing my new design, the said sheet being of conventional thickness.

I claim:

The ornamental design for a sheet of decorative material or the like, as shown.

CLIFFORD BROOKS STEVENS.
